UNITED STATES PATENT OFFICE.

WALTER H. COOK, OF NEW ORLEANS, LOUISIANA.

SHOCK-ABSORBER FOR AUTOMOBILES.

1,070,842.

Specification of Letters Patent. Patented Nov. 25, 1913.

Application filed August 14, 1913. Serial No. 784,784.

To all whom it may concern:

Be it known that I, WALTER H. COOK, a citizen of the United States, residing at New Orleans, in the parish of Orleans and State of Louisiana, have invented new and useful Improvements in Shock-Absorbers for Automobiles, of which the following is a specification.

This invention relates to improvements in shock absorbers of that general type which is illustrated in my prior Patent No. 1,058,413, granted April 8, 1913, and which embodies a transverse main spring, a cushioning element, and a shock transmitting element, these parts being in a common vertical plane and being so related that the cushioning element and the main spring mutually coact to eliminate minor tremors or vibrations which would be otherwise uncared for.

The present invention comprises a specific organization of the parts aforesaid, which is particularly applicable to cars of the well known "Hupmobile" type, and wherein the improved shock absorber, disposed transversely of the car, supplements the action of the springs or other shock absorbing agencies at the sides of the car.

Embodiments of the invention are illustrated in the accompanying drawings, wherein:

Figure 1 is a perspective view showing an application of the improved shock absorber to the rear end of a car of the "Hupmobile" type; Fig. 2 is a similar view showing a slightly modified construction; Fig. 3 is an elevation, looking toward the rear end of the car, showing a further modified construction; and Fig. 4 is a side elevation showing details of the construction disclosed by Fig. 3.

Similar characters of reference designate corresponding parts throughout the several views.

In the construction shown in Fig. 1, the main spring 1 is secured at its center directly to the rear bar of the chassis A, and is arranged above the other elements of the shock absorber. The cushioning element, as 2, as is usual in constructions of the type identified, preferably consists of an elongated pneumatic tube. The support for the cushioning element 2 consists of a substantially rigid bar 3, forming a bed for said cushioning element, and having at its ends upright hangers 4. The hangers 4, at their upper ends, are connected to longitudinally dis-

posed arms 5 which are usual in "Hupmobile" cars, and in the ordinary constructions are directly attached to the ends of the rear spring. The arms 5 are mounted upon the ends of the rear axle casing B and the hangers 4 obviously suspend the bed 3 and the cushioning element from said arms. The shock transmitting element, in the instance of Fig. 1, comprises a pair of bars 6 which engage the upper side of the cushion 2 and are arranged between the latter and the main spring 1. The bars 6 are connected at their inner ends to the bed 3 and at their outer ends to the spring 1. Said bed is provided with upright alining ears 8 which are arranged at the sides of the cushioning element and the inner ends of the bars 6 are pivoted between the ears 8. The connections between the bars 6 and the spring 1 comprise upright ears 9 provided at the ends of said bars and links 10 which are pivotally arranged between the ears 9 and are also pivoted to the ends of the spring 1.

The construction shown in Fig. 1 is especially desirable where the car is relatively heavy or is to be used on rough roads, and the spring 1, by reason of the violence of the shocks, may occasionally be extended to its full capacity. With this possibility in view, the inner ends of the bars 6 are spaced from one another to provide a clearance 11 and the spring is provided at its center and on its under side with a bumper 12, which, in the event that the spring is nearly straightened, enters the clearance 11 and engages upon the central portion of the cushion 2. In this way any sudden jolt that would otherwise tend to straighten or flatten the spring is arrested. It is preferable to provide the exposed portion of the cushion 2 with a band or layer 13 of rawhide or some other suitable tenacious material which will protect said cushion against wear consequent to the engagement therewith of the bumper 12.

The construction shown in Fig. 2 embodies the same general arrangement of parts as is shown in Fig. 1, but differs in that the shock transmitting element, instead of comprising a pair of bars 6, comprises a single bar 6^a, coextensive with the cushion 2 and pivoted at its center, as at 14, to the bed 3.

In cases where it may be desired to economize space below the axle B, the construction shown in Figs. 3 and 4 may be employed. In this case, the spring is arranged

below the cushioning element instead of above it, as in the embodiment described. The arms 5 are again utilized to suspend the bed for the cushioning element, but in this embodiment the bed, as 3^a, is in the plane of the upper ends of said arms and is substantially co-planar with the rear bar of the chassis.

The shock transmitting element may comprise either a pair of bars like the construction shown in Fig. 1, or a single bar, like the construction shown in Fig. 2. As shown, a pair of bars 6^a are employed which, at their inner ends, are pivoted between lugs 8^a upstanding from the bed 3^a. Vertically disposed links 10^a connect the outer ends of the bars 6^a and of the spring 1^a, and the latter is secured at its center to a bracket 15 which, in turn, is connected to the center of the rear bar of the chassis A.

In all the constructions described, the elements of the shock absorbing agency are arranged in a common vertical plane, transverse to the chassis, and the shock transmitting element produces a wave-like compression of the cushion 2, in unison with the action of the spring, thereby steadyng the latter and minimizing the rebounds.

Having fully described my invention, I claim:

1. In a shock absorber, the combination with a chassis, an axle casing, and a pair of longitudinally disposed arms secured at the ends of the axle casing, of a main spring secured at its center to the center of a transverse bar of the chassis, a cushioning element in the plane of said spring, a rigid bed for said cushioning element connected at its ends to the ends of said arms, a shock transmitting element pivotally connected to the central portion of said bed and engaging upon said cushioning element, and links connecting the outer ends of said shock transmitting element and said main spring.
2. In a shock absorber, the combination with a chassis, an axle casing, and a pair of longitudinally disposed arms secured at the ends of the axle casing, of a main spring secured at its center to the center of a transverse bar of the chassis, a cushioning element arranged below said spring in the plane thereof, a rigid bed for said cushioning

element, hangers depending from said arms and carrying said bed, a shock transmitting element pivotally connected to the central portion of said bed and engaging upon said cushioning element, and links connecting the outer ends of said shock transmitting element and said main spring.

3. In a shock absorber, the combination with a chassis, an axle casing, and a pair of longitudinally disposed arms secured at the ends of the axle casing, of a main spring secured at its center to the center of a transverse bar of the chassis, a cushioning element arranged below said spring in the plane thereof, a rigid bed for said cushioning element, hangers depending from said arms and carrying said bed, a shock transmitting element comprising a pair of bars pivotally connected at their inner ends to said bed and engaging upon said cushioning element, links connecting the outer ends of said bars and said main spring, the pivoted inner ends of the bars being spaced to expose the central portion of the cushioning element, and a bumper provided at the center of said main spring to engage the exposed central portion of the cushioning element.

4. In a shock absorber, the combination with a main spring connected at its center to the chassis, an elongated air cushion below the main spring, a bed supporting the air cushion, a pair of shock transmitting bars arranged between the main spring and the air cushion and engaging the upper side of the latter, links connecting the outer ends of said bars and the outer ends of the main spring, pivotal connections between the inner ends of the bars and the bed, said pivotal connections being arranged in spaced relation to expose the central portion of the air cushion, and a bumper provided at the center of the main spring for engagement with the exposed central portion of the air cushion.

In testimony whereof I have hereunto set my hand in presence of two subscribing witnesses.

WALTER H. COOK.
